C. F. BRAUN.

HEAT EXCHANGER.

APPLICATION FILED MAR. 13, 1919. RENEWED AUG. 20, 1920.

1,376,135.

Patented Apr. 26, 1921.

UNITED STATES PATENT OFFICE.

CARL F. BRAUN, OF SAN FRANCISCO, CALIFORNIA.

HEAT-EXCHANGER

1,376,135.

Specification of Letters Patent. Patented Apr. 26, 1921.

Application filed March 13, 1919, Serial No. 282,258. Renewed August 20, 1920. Serial No. 404,957.

To all whom it may concern:

Be it known that I, CARL F. BRAUN, a citizen of the United States, residing in the city and county of San Francisco, and State of California, have invented new and useful Improvements in Heat-Exchangers, of which the following is a specification.

This invention relates to a heat exchanger and particularly pertains to improvements 10 in structures of the type shown in my patent entitled Heat exchanger, No. 1,284,868, bearing date of November 12th, 1918.

Due to the confined quarters in which heat exchangers are sometimes installed, it is desirable to provide the shell of a heat exchanger with means whereby the tube nest may be readily removed from either end of the exchanger or inspected if desired. It is the principal object of this invention to provide a heat exchanger shell embodying such improvements.

The invention consists of a central, cylindrical shell within which a heating element is mounted and which element may be removed from either end of the shell by the removal of the heads bolted thereon.

The invention is illustrated by way of example in the accompanying drawings, in which—

30 Figure 1 is a longitudinal, central section of the heat exchanger showing the details of its construction.

Fig. 2 is an end view in elevation further illustrating the arrangement of the intake and outlet pipes of the shell.

In the drawings, 10 indicates a cylindrical shell of the same general construction as shown in my copending application entitled Heat exchanger, bearing Serial Number 40 253,811 and filed Sept. 12th, 1918. This shell is formed with opposite bolting flanges 11 and 12 which circumscribe the ends thereof and are adapted to receive clamping bolts 13. Mounted within the shell is a heating element 14. This element is also disclosed in the copending application previously referred to, and consists of a central rod 15 upon which a plurality of disk baffle plates

16 are mounted. These plates are held in spaced relation to each other by spacing tubes 17. The spacing tubes have opposite wings 18 which are arranged to divide the shell 10 into two compartments. The plates 16 are perforated to receive a plurality of tubes 19 and also to allow circulating space around the tubes.

The tube bundle is provided at its opposite ends with tube sheets 20 and 21 by which the various tubes are held in fixed spaced relation to each other and permanently assembled so that the entire heating unit comprising the tubes, the baffle members 16, the partition members 18 and the end sheets may be completely removed when desired. The tube sheet 21 is fitted with a removable dome 22 which forms a chamber through which the ends of the various tubes may communicate. The portion of the heating element upon which the tube sheet 21 and the dome 22 are mounted extends through the end of the shell 11 and is there covered by a cap 23 adapted to be bolted against the flange 12 by means of the bolts 13. It will thus be evident that by removal of this cap the ends of all of the tubes will be completely exposed and may be inspected, or, if desired, the dome 22 may be removed without obstruction from the shell. The opposite end of the heating element terminates flush with the end of the shell 11 and a head member 24. It may therefore abut against it as it is bolted to the flange 11 by the bolts 13. The head 24 is cylindrical and is formed with a small flange adapted to receive cap screws 25 which pass through the tube sheet 20 and thus attach the heating unit to this casting so that when the head is loosened the heating element may be drawn out therewith. The end of the head 24 has a removable cover plate 26 held in position by cap screws 27. Due to the use of this plate the tube sheet 20 may be readily inspected. It will be understood that the shell is provided with the customary inlet and outlet connections 28 and 29 and that the head 24 will be provided with inlet and outlet pipes 30 and 31 by which a constant double circulation of fluids may be effected around and through the heating element. A partition 24' is formed across the steam head 24 and thus divides this member into two compartments, agreeing with those on the opposite sides of wings 18. This separates the inlet and outlet pipes 30 and 31.

In the operation of the present invention 105 the heat exchanger is assembled, as shown in Fig. 1, and may be caused to function in the ordinary manner, as set forth in the application previously mentioned. In the event that the heating element is to be inspected, this operation may be performed by 110 removing the cap 23 and the dome-piece 22

to gain access to one end of the heating element or by removing the cover plate 26 to inspect the other end of the heating element. In case the heating element is to be removed 5 from the shell 10, the bolts 13 are first unfastened and the head member with the completely assembled heating element drawn through the shell and out the opening over which the head member is normally fastened. If it so happens that there is insufficient clearance for the removal of the heating element from this opening, the heating element is partially withdrawn from the shell and the cap screws 25 removed to dis- 10 connect the tube sheet 20 from the channel member 24. It will then be possible, after removal of the shell cap 23, to withdraw the heating element from that end of the shell. Thus it will be seen that the installation of 15 the heat exchanger is not limited by the particular clearance afforded at one end of the shell but is merely limited to clearance at either end of the shell sufficient to allow the complete withdrawal of the heating ele- 20 ment from the shell. It will also be evident that the opposite ends of the heating element may be readily inspected without in any way molesting the heating element structure and by a simple and convenient operation. 25 Having thus described my invention, what I claim and desire to secure by Letters Patent is:

1. A heat exchanger comprising a shell, a tubular heating element detachably positioned therein, a head member adapted to close one end of the shell and to support one 30 end of the heating element and a cover cap upon the opposite end of the shell within which the opposite end of the heating ele- 35 ment is freely mounted.
2. A heat exchanger comprising a cylindrical shell, fluid circulating connections therewith, a heating element slidably positioned within said shell and extending from one 40 end thereof, a cover cap sealing one end of the shell and inclosing the extending end of the heating element and an end head member to which the opposite end of the heating element is secured and which in turn 45 closes the opposite end of the shell.
3. A heat exchanger comprising a cylindrical shell, fluid circulating connections there- 50

with, a heating element slidably positioned within said shell and extending from one end thereof, a cover cap sealing one end of the shell and inclosing the extending end of the heating element, a head member to which the opposite end of the heating element is secured and which in turn closes the opposite end of the shell, and a cover plate forming a part of the end casing and adapted to disclose the end of the heating element when removed. 55

4. A heat exchanger assembly comprising a tubular shell, a heating unit comprising a plurality of tubes removably positioned within said shell, a head member adapted to close one end of the shell and to support one end of the heating unit, and a cover cap upon the opposite end of the shell within which the opposite end of the heating unit is freely mounted. 60

5. In a heat exchanger, a shell having open ends and of substantially uniform cross section throughout, a nest of tubes mounted therein and removable from either end thereof, a tube sheet on said tubes forming a barrier between the shell chamber and interior of the tubes, means for removably securing the tubes and sheet in position within the shell and independent end closures removably secured on the shell, one of said closures being imperforate and completely surrounding one end of said nest of tubes. 65

6. In a heat exchanger, a shell having open ends and of substantially uniform cross-section throughout, a nest of tubes mounted therein and removable from either end thereof, a tube sheet on said tubes forming a barrier between the shell chamber and interior of the tubes, means for removably securing the tubes and sheet in position within the shell and heads removably secured to the ends of said shell, one of said heads being provided with an internal flange 90 to which the adjacent tube sheet is connected, whereby to entirely close the space between the tubes and shell. 95

In testimony whereof I have hereunto set my hand in the presence of a subscribing witness.

CARL F. BRAUN.

Witness:

JOHN F. MILLER.
